UNITED STATES PATENT OFFICE.

DANIEL CARLOUGH, JR., AND EUGENE BOGERT, OF PATERSON, NEW JERSEY.

WINDOW FRAME AND SASH.

1,288,680.

Specification of Letters Patent. Patented Dec. 24, 1918.

Application filed February 28, 1916. Serial No. 80,891.

To all whom it may concern:

Be it known that we, DANIEL CARLOUGH, Jr., and EUGENE BOGERT, both citizens of the United States, residing at Paterson in the 5 county of Passaic, State of New Jersey, have invented certain new and useful Improvements in Window Frames and Sash; and we declare the following to be a full, true, and exact description of said invention, such as 10 will enable others skilled in the art to which it appertains to make use of the same.

The present invention relates to window frames and sash, particularly when made of metal in structural shapes, usually of steel:

15 One of the objects of our invention is to provide a simple and inexpensive construction of sashes and frames so that the same will be effectively weather-proofed at their edges.

20 With this and other objects in view, our invention consists of certain novel features of construction, combination and arrangement of parts as will be more fully pointed out and described in the appended claims.

25 In the drawings, Figure 1 represents the outside view of a window, the sash of which is pivoted;

Fig. 2 is a section on the line 2—2 through the pivot of the window;

30 Fig. 3 is a section on the lines 3—3 of Fig. 1;

Fig. 4 is a section on the lines 4—4 of Fig. 1;

Fig. 5 is a construction which may be used 35 instead of that shown in Fig. 3;

Fig. 6 is an inside view of a double sash window, of which Fig. 7 is an enlarged section taken partly on the line 7—7 and partly on the line 7'—7' of Fig. 6.

40 Fig. 8 is a section on the line 8—8 of Fig. 6.

The corresponding parts are referred to both in the drawings and in the specification by similar reference characters.

45 Referring particularly to the pivoted sash construction, one form of which we have illustrated in Figs. 1 to 4 inclusive, it will be seen that the frame is made up of the bars 10 having a section shown in Figs. 2—4 inclusive. In this form chosen for purposes of 50 illustration, this section is shown as substantially a T with a rib extending along the flange parallel to the web of the T. A part of the flange of the T is set in the wall W 55 and an angle bar 11 is fastened to the web of

the bar 10 with one leg of the angle also inserted in the wall W. It will be understood that the bars 10 are welded or otherwise attached at their ends to form the rectangular frame.

60 The sash, in the form chosen for purposes of illustration, is made up of T-bars 12 having a rib extending along the flange and parallel to the web, preferably on each side of the web. The glass G is fastened in the 65 sash by the putty P, the glass resting on the inner rib.

In order to provide pivots on which the sash can be turned, we attach to the frame a block 13 and to the sash a block 14, these 70 blocks being provided with a pivot pin 15, and the blocks are arranged so that at the bottom they will carry the weight of the window with just sufficient clearance between the upper blocks 13—14 to provide 75 easy sliding motion between them.

The window, as so far described, would, of course, have an opening between the sash and the frame in order to provide clearance to permit the sash to swing into the 80 closed position. It is an important part of our invention that we provide means by which this clearance crack can be effectively closed. In the form which we have chosen for purposes of illustration, the window 85

is supposed to swing, for purposes of ventilation, so that the right-hand portion of the sash moves outward or toward the spectator, the opposite or left-hand side, of course, moving in the opposite direction. The portion to the right of the axis of the pivot 15 is constructed as shown in Fig. 3. The channel member 16 provided with the rib 17 is permanently fastened to the web of the frame bar 10, the two legs of the channel and 90 the ribs 17 being arranged in such a way

that when the window is in closed position as shown in Fig. 3, one leg of the web contacts with the rear edge of the T-bar 12, the rib on the T-bar 12 contacts with the other leg 95 of the channel member 16, and the rib 17 contacts with the inner side of the flange or the T-bar 12. It will thus be seen that we have provided three contact points which

100 wind or water must pass before entering the building. Moreover, this arrangement is particularly effective since we have provided a path which by returning on itself, offers additional resistance to the wind and also in 105 the event that water laden air is driven past

110

the first contact point, the incoming air by reason of the bends in its path, will lose its velocity, and the water will therefore be dropped and will run down through the vertical openings in the channel members from which it may be drawn off through any suitable "weep" holes in the bottom of the sash or frame.

The portion of the sash to the left of the pivot in Fig. 1 is provided with the construction shown in Fig. 4. In this portion the channel bar 16' is attached to the sash and swings with the same. When the sash is closed, however, we have obtained the same 15, three-point contact as will be evident from an inspection of Fig. 4.

At the portion opposite the blocks 13—14, there would be a chance for water to be driven through the narrow opening necessarily between these two blocks, and in order to prevent this, we provide a guard 18 which is bent to carry off water which otherwise might be driven through this small crack.

25 In Fig. 5 we have shown a construction which may be used at the top of the window to the right of the pivot, and in place of the structure shown in Fig. 3. An inspection of Fig. 3 will show that any water 30 which passes through the crack between the sash and the frame, and which should find its way past the contact points between the two ribs and between the web of the T-bar 12 and the channel bar 16, would directly 35 enter the building. This, of course, is not true of the arrangement shown in Fig. 4, because the channel bar is there fastened to the web of the T-bar 12, and any water passing through the crack between the sash and 40 the frame would have to work upward instead of downward. In the arrangement shown in Fig. 5, we have provided a pair of channel bars, one 30 fastened to the sash and the other 31 to the frame in such a way 45 that as the frame is swung into place, the two legs of these channel bars will contact with each other. Any water which may find its way into the channel of the lower channel bar, passes out through the weep holes 50 indicated.

We may also embody our invention in a window having sliding instead of pivoted sash. Such a construction we have illustrated in Figs. 6—8. In these figures, the 55 frame is made up of the bars 20 connected at their ends in any suitable manner, to which are attached a pair of channel bars 21—22 in any suitable manner, such as the screws 23. The sash is made up of the same 60 kind of T-bars as illustrated in Figs. 1—4 and the channel bars 21—22 are provided with the ribs as shown in Fig. 7. Also as shown in that figure, these ribs, when the upper and lower sash are in place, act as guide- 65 ways and weathering-contact points for the

sash. The angle iron 24 is provided to hold the upper sash in place, and preferably the channel bar 21 is provided with a rib 25 so that the lower sash will have a relatively small contact area with the channel 21. Fig. 70 8 shows one form of a construction by which the space between the upper and lower sash may be closed when the window is closed. We have provided in this construction a bar 26 attached to the upper sash and a bar 75 27 attached to the lower sash, these bars being arranged so that their faces come into angular contact when both sashes are closed, thus effectively shutting off all air space between the two sashes. 80

Referring particularly to Fig. 7, it will be noted that by providing the ribs on the sash and on the frame channels, and also providing these channels so that the edges of the web of the T-bars of the sash fit thereagainst, any wind pressure or water tending to enter the building must pass three points of contact at least, and also through a crooked path, which, as has been pointed out before, not only cuts down the velocity 90 of the air and therefore, the quantity passing through in case the contact points are not perfect, but also causes the water to drop out of any moisture laden air passing through these cracks. 95

While we have shown our invention in its preferred form, it should be understood that we do not desire to confine ourselves to the specific forms illustrated. It is obvious that many variations of the shapes shown could be substituted for those illustrated without departing from our invention as defined in the appended claims. 100

We claim:—

1. A window and sash, each of said parts 105 having a member projecting from its edge toward the other part, and one of said members having a body portion at right angles to the projecting member and a rib extending along the edge of the projecting member, and a third member contacting with the projecting member, its rib and the edge of the body portion, when the sash is closed. 110

2. A window frame having a T-shaped section, a sash having a T-shaped section, 115 the flanges of said T-shaped sections being in the same plane, and each provided with a rib extending along the flange parallel with the web thereof, and a member attached to one of said T-shaped sections and contacting, when the sash is closed, with the edges of the ribs and also with the flange of the other of said T-shaped sections. 120

3. A window frame having a T-shaped section, a sash having a T-shaped section, 125 the flanges of said T-shaped sections being in the same plane and each provided with a rib extending along the flange parallel with the web thereof, and a channel-shaped member having a rib extending along one of its 130

legs, and attached to one of said T-shaped sections, the rib on said channel-shaped member contacting with the flange of the other of said T-shaped members, and the 5 ribbed leg of said channel-shaped member with the edge of the rib on said flange, and the other leg of the channel member contacting with the edge of the web of the

other of said T-shaped members, when the sash is closed.

DANIEL CARLOUGH, JR.
